UNITED STATES PATENT OFFICE.

ROBERT W. ROSE, OF MARBLEHEAD, MASSACHUSETTS.

STRAIGHT-ARM HOIST FOR DUMPING-VEHICLES.

1,294,173.

Specification of Letters Patent. Patented Feb. 11, 1919.

Application filed February 21, 1917. Serial No. 150,059.

To all whom it may concern:

Be it known that I, ROBERT W. ROSE, a citizen of the United States, and resident of Marblehead, in the county of Essex and

5 State of Massachusetts, have invented an Improvement in Straight-Arm Hoists for Dumping-Vehicles, of which the following description, in connection with the accompanying drawings, is a specification, like let-

10 ters on the drawings representing like parts.

My present invention is an improved hoisting apparatus comprising a pair of substantially straight arm hoisting levers, having one end pivotally secured to the dumping wagon body and the other end adapted to roll upon a guideway. The straight arm levers arranged at either side of the wagon body, are normally folded between the body and the vehicle frame in a substantially

20 horizontal position, to save room, and by the provision of novel means to permit the first hoisting action to raise or tilt the vehicle body and thus give a working inclination to the hoisting levers, I am enabled to produce

25 a simple and efficient construction. I accomplish this purpose by providing a substantially perpendicularly extending strut from the hoisting levers and so arranging the cables or chains which actuate the said levers

30 to provide the initial vertical lift through said strut, as the chain or cable is wound up on the shaft or drum, securing a sufficient inclination to enable the lever itself to then take up the thrust, having been lifted out

35 of its substantially horizontal position, and complete the inclination of the dumping body. The present apparatus is an improvement upon my prior hoisting mechanism shown in my application, Ser. No. 46657, filed

40 August 21, 1915, and my application, Ser. No. 118,022, filed September 1, 1916, combining certain advantageous features of each of said prior apparatuses while greatly simplifying the construction.

45 Referring to the drawings illustrating a preferred embodiment of the invention,

The figure shows a side view of a support and wagon body illustrating, in dotted lines, the raised position.

50 In dumping bodies of this type it is customary to build such a body upon the chassis of an automobile or other vehicle, but the chassis is not shown, it being understood that any suitable vehicle support may be employed. To fit upon the chassis, I provide a pair of side arms 1 across which are beams

2, 3, 4 and 5, on which beams are a pair of longitudinal supports 6, one on either side of the vehicle and adapted to receive the tilting body 7 in lowered position, the cross beams 8, 8, of said body, resting directly upon the parallel supports 6, as clearly shown in the drawing. Secured at each side to a support 6 and its adjacent side frame 1 is a track 9 slightly inclined, which track 60 may be of angle iron or other suitable construction. Said track has its upper end leading adjacent the shaft 10, which preferably extends across the wagon in suitable bearings in the support 6, which shaft is adapted to be rotated by a series of gears and pinions 11, 65 12, 13 and 14, the latter being actuated by a crank or other power, in a well known manner.

The tilting body 7 is pivoted at 15, near its 70 rearmost end, to the support 6, and in order to effect the tilting action, I provide a pair of straight arm levers, each lever being the duplicate of the other and arranged at either side of the body. This hoisting lever is 75 shown at 16 and has one end pivoted at 17 to a cross brace 18 on the body 7, and at the other end of said lever is a roll 19, preferably flanged and adapted to traverse the track 9. Near the pivoted end 17 on each lever, I provide a perpendicularly extending strut 20, preferably uniting the struts on either side by a cross rod 21, which latter engages the chain or cable 22 having one end secured to the shaft 10 and the other end to the rod 23, which rod may also constitute the bearing for the flanged roller 19. Two of these chains 22 are provided, both adapted to be wound upon the shaft 10 as the latter is rotated through the gears 11, 12, 13 and 14. 80 85

In the operation of the hoisting mechanism just described, when the body 7 is in lowered position, the first winding action of the chains 22 on the axle 10 results in securing a substantially vertical lift on the pivoted end 17 of the straight lever 16, such lift gradually tilting the body 7 upwardly

90 on its rear pivots 15 and giving a sufficient inclination to the lever 16 as the same rolls upon the track 9, to permit said levers efficiently to take up the tilting thrust when the struts 20 and rod 21 have been raised to the extent permitted by the hoisting action of the chain 22. From this preliminary inclined position, the continued winding of the chains 22 then moves the partially inclined lever 16 during the completion of the hoist-

ing action, causing the rolls 19 on said levers to traverse the track 9 until the completely inclined position as shown in dotted lines, is reached. This construction permits an 5 extremely quick, economical and efficient hoisting mechanism to be provided, and one capable of handling small loads readily. Furthermore, the complete folding down of the hoisting levers to approximately horizontal 10 position, affords a low center of gravity, and still enables the hoisting mechanism to be constructed for the transmission of bearings, strains, etc., from the bottom of the tilting body to the frame supports on top 15 of the chassis, eliminating depending tracks, and the like.

My invention is further described and defined in the form of claims as follows:

1. Hoisting apparatus of the kind described, comprising a support, a dumping body pivoted to said support and adapted to be hoisted at an inclination therewith, a pair of straight arm hoisting levers, one end of each of said levers being pivoted to the body 20 and the other end carrying a roll, tracks for said rolls on each side of the supporting frame, a pair of chains from the roll ends of said levers to a shaft, said shaft positioned above the said track, a perpendicularly extending strut on each lever adjacent the pivoted end, 25 a rod connecting said struts and bearing on the chains from the shaft to the roll ends of said levers, whereby the said levers may be in approximately a horizontal position when the body is lowered and secure an initial lifting to permit them to take up and complete the thrusting action.
2. Hoisting apparatus of the kind described, comprising a support, a dumping body pivoted to said support and adapted to be hoisted at an inclination therewith, a pair of straight arm hoisting levers, one end of each of said levers being pivoted to the body 30 and the other end carrying a roll, tracks for said rolls on each side of the supporting frame, a pair of chains from the roll ends of said levers to a shaft, said shaft positioned above the said track, a perpendicularly extending strut on each lever adjacent the pivoted end, a rod connecting said struts and bearing on the chains from the shaft to the roll ends of said levers, whereby a substantially vertical lifting action through said 35 strut is secured, sufficient to raise the levers to an inclined position for continuing the thrusting action in the hoisting operation.
3. Hoisting apparatus of the kind described, comprising a support, a dumping body pivoted to said support and adapted to be hoisted at an inclination therewith, a pair of straight arm hoisting levers, one end of each of said levers being pivoted to the body and the other end carrying a roll, 40

straight tracks slightly inclined for said rolls 45 at each side of the supporting frame, a pair of chains from the roll ends of said levers to a shaft, said shaft positioned above the said track, a perpendicularly extending strut on each lever adjacent the pivoted end, 50 a rod connecting said struts and bearing on the chains from the shaft to the roll ends of said levers, whereby the said levers may be in approximately a horizontal position when the body is lowered and secure an initial lifting to permit them to take up and complete the thrusting action.

3. Hoisting apparatus of the kind described, comprising a vehicle frame, a dumping body carried thereby and adapted to be 60 hoisted at an inclination therewith, a pair of movable hoisting levers, one end of each lever having a pivotal connection with said body, and the other end of each lever carrying a roll, a strut on each lever intermediate its end, tracks for each roll at the side of said frame, a winding shaft having its axle located above the tracks and substantially in vertical alinement with the outer ends of said struts when the levers are in 65 lowered position, flexible connections from the roll ends of each lever with a bearing over the struts to said winding shaft, whereby the initial hoisting of the body will be effected by the substantial vertical lifting 70 action of said flexible connections, until said struts have reached a height substantially on a horizontal plane with the windingshaft, whereupon the continued hoisting action will shift to the outer ends of said levers.

In testimony whereof, I have signed my name to this specification, in the presence of two subscribing witnesses.

ROBERT W. ROSE.
